UNITED STATES PATENT OFFICE.

ALFRED GERALD PAFFENBARGER, OF LOS ANGELES, CALIFORNIA.

WATERPROOF SEAM FOR COMPOSITION-BOARD.

1,299,999.

Specification of Letters Patent. Patented Apr. 8, 1919.

Application filed July 22, 1918. Serial No. 246,148.

To all whom it may concern:

Be it known that I, ALFRED G. PAFFENBARGER, a citizen of the United States, and a resident of Los Angeles, in the county of 5 Los Angeles and State of California, have invented a new and Improved Waterproof Seam for Composition-Board, of which the following is a full, clear, and exact description.

10 This invention relates to a waterproof joint for composition and other boards whereby the same can be used for roofs, walls and other exterior work, and the principal object of the present invention is to 15 provide an overlapping flexible seam joiner of comparatively simple and inexpensive construction and so designed that the boards can be easily and quickly laid and watertight joints secured.

20 A more specific object of the invention is the provision of a flexible seam cover or joiner in the form of a fabric strip of novel construction which is impregnated with a waterproof material, there being such a 25 strip along two edges of a board so that when the boards are laid the seam cover or joiner on one board will overlap the side edge and an end edge of two adjacent boards, and as a consequence all the seams 30 will be sealed by a flexible member, and the entire external surface of the roof or wall made in this manner will be further waterproofed by a coating of suitable waterproof material, and further protection may be obtained by a coating of paint.

Another object of the invention is the provision of novel fastening devices attached to the boards whereby the latter can be easily, quickly and securely fastened to the sheeting 40 boards or other supporting surface.

With such and other objects in view, the invention comprises various novel features of construction and arrangement of parts which will be set forth with particularity 45 in the following description and claims appended hereto.

In the accompanying drawing, which illustrates one embodiment of the invention and wherein similar characters of reference 50 indicate corresponding parts in all the views,

Figure 1 is a plan view of a portion of a roof made of composition or like boards with the improved waterproof joint employed;

Fig. 2 is an enlarged sectional view on the line 2—2, Fig. 1.

Fig. 3 is a detail sectional view of one edge of a board before being applied;

Fig. 4 is a perspective view of a portion 60 of the seam joiner or cover;

Fig. 5 is a perspective view of a composition board with the seam joiner applied to two edges thereof.

Referring to the drawing, 1 designates 65 sections of composition board or equivalent material now in common use for forming walls and partitions. These sections are fastened to a suitable supporting surface formed by sheeting boards or the like, and 70 the joints are rendered waterproof by an improved overlapping flexible seam joiner that constitutes the subject matter of the present invention, and which makes it possible to use composition and equivalent 75 boards for roofs, walls and other exterior purposes. Along two edges of a board 1, as shown in Fig. 5, is arranged the seam joiner or cover A. In the present instance this is made as an L-shaped piece of cotton fabric, canvas or the like, impregnated with paraffin or equivalent waterproof compound. The joiner is several inches wide, so that one-half of each member is cemented or otherwise secured to the outer surface of the 80 board 1 with the rest of the strip projecting beyond the board so as to overlap the next boards adjacent to it. Extending longitudinally and centrally of each member of the L-shaped seam joiner or cover and secured 85 thereto by stitches 2 is a narrow strip 3 of cotton, canvas or other fabric which is impregnated with paraffin or equivalent waterproof material. Thus, as shown in Fig. 4, the joiner is T-shaped in cross-section and 90 the strip 3 will lie between adjacent edges 4 and 5 of juxtaposed boards 1, as clearly shown in Fig. 2. If the composition board is about one-quarter of an inch thick the sealing strip 3 will be about one-half of an 95 inch thick, so that the free edge 6 will lap under the board to which the joiner is attached. The joiner or cover A is cemented 100 to the composition board along the two edges thereof, as shown in Fig. 5, and consequently when the boards are laid edge to edge all the joints or seams will be thoroughly sealed and covered. The overlapping portion 7 of the joiner A will be cemented to the next board, and when all the 105

110

- boards are laid and the joiners sealed, a coating of waterproof material 8 will be applied on the roof or wall. The boards are fastened at the edges 9 and 10 that are devoid 5 of a joiner by nails 11, as shown in Fig. 1, the nails being close to the margins, so that the flap 7 of the joiners will cover the nails and seal the perforations made thereby. The other two edges, that is to say, the edges 10 to which the joiner is applied, are provided with a plurality of metal fasteners in the form of flat pieces 12 fastened to the under side of the board and projecting therefrom, the fastening being effected by rivets 13. 15 The projecting ends of the fasteners 12 are perforated so that a tack 14 can pass therethrough and be driven into the sheeting board 15. In this manner the boards are quickly laid and secured to the sheeting board or other foundation. 20

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have 25 it understood that the device shown is merely illustrative and that such changes may be made when desired as fall within the scope of the appended claims.

Having thus described my invention, I 30 claim as new and desire to secure by Letters Patent:

1. A board having a seam joiner attached to an edge thereof, said joiner comprising a flexible strip of T-shaped cross-section, a portion 35 of the top member adhering to the top surface of the board and the remainder of the top member projecting beyond the edge of the board, and the vertical member of the strip being cemented to the edge of the board.
2. A board having a seam joiner attached to an edge thereof, said joiner comprising a flexible strip of T-shaped cross-section, a portion 40 of the top member adhering to the top surface of the board and the remainder of the top member projecting beyond the edge of the board, and the vertical member of the strip being cemented to the edge of the board, and also cemented to the under 45 side of the latter, and fasteners secured to the under side of the board at the edge having the strip, and said fasteners projecting outwardly from the board.
3. A board having a seam joiner along 50 two contiguous edges, said joiner being at-

tached to the outer face of the board and projecting beyond the edges thereof and also having a member covering the edges and lapping under the board.

4. A board having a seam joiner along 55 two contiguous edges, said joiner being attached to the outer face of the board and projecting beyond the edges thereof and also having a member covering the edges and lapping under the board, and fasteners secured to the under surface of the board and projecting beyond the edges and lying under the projecting portions of the seam joiner. 70

5. The combination of a plurality of 75 boards laid edge to edge and each board having along two contiguous edges a seam joiner which comprises a strip of fabric impregnated with waterproof material and having a portion adhering to the top surface of the board and another portion projecting 80 therefrom to overlap adjacent boards and also having a portion covering the edge and lapping under the board.

6. The combination of a plurality of 85 boards laid edge to edge and each board having along two contiguous edges a seam joiner which comprises a strip of fabric impregnated with waterproof material and having a portion adhering to the top surface of the board and another portion projecting therefrom to overlap adjacent boards and also having a portion covering the edge and lapping under the board, fastening members secured to the under side of each board at those 90 edges having the seam joiner and projecting beyond such edges, a foundation on which the boards are placed, and fasteners passing through the fastening members and driven into the foundation.

7. The combination of a plurality of 100 boards laid edge to edge and each board having along two contiguous edges a seam joiner which comprises a strip of fabric impregnated with waterproof material and having a portion adhering to the top surface of the 105 board and another portion projecting therefrom to overlap adjacent boards and also having a portion covering the edge and lapping under the board, fastening members secured to the under side of each board at those edges having the seam joiner and projecting beyond such edges, a foundation on which the boards are placed, fasteners passing through the fastening members and driven into the foundation, and fasteners 110 passing through the boards at the edges that do not have a seam joiner, said last-mentioned fasteners of each board being covered by seam joiners of adjacent boards. 115

ALFRED GERALD PAFFENBARGER.
